UNITED STATES PATENT OFFICE.

JOSEPHINE SHIVELY, OF SAUSALITO, CALIFORNIA.

DESIGN FOR AN INCENSE BURNER.

Application filed December 1, 1922. Serial No. 4,453. Term of patent 7 years.

To all whom it may concern:

Be it known that I, JOSEPHINE SHIVELY, a citizen of the United States, and resident of the town of Sausalito, county of Marin, State of California, have invented a new, original, and ornamental Design for an Incense Burner, of which the following is a specification, reference being had to the accompanying drawings, forming a part thereof.

In the drawings:

Fig. 1, is a front view of the incense-burner;

Fig. 2, is a rear view of the same;

Fig. 3, is a side view of my incense-burner.

The important features of my design reside in the employment of a grotesque figure, a three-leaved shamrock to portray the facial expression, and the use of a four-leaved shamrock to represent the back of the head, while faintly outlined on the upper portion of the base of the burner is a snake which encircles a basin-like depression for incense.

I claim:

The ornamental design for an incense-burner as shown and described.

In testimony whereof I have hereunto affixed my signature.

JOSEPHINE SHIVELY.
